UNITED STATES PATENT OFFICE.

JOSEPH A. CYPERT, OF KANSAS CITY, MISSOURI.

COMB.

1,340,379.

Specification of Letters Patent. Patented May 18, 1920.

Application filed November 19, 1918. Serial No. 263,131.

To all whom it may concern:

Be it known that I, JOSEPH A. CYPERT, a citizen of the United States, residing at Kansas City, in the county of Jackson and 5 State of Missouri, have invented certain new and useful Improvements in Combs, of which the following is a full, clear, and exact description, such as will enable others skilled in the art to which it appertains to 10 make and use the same.

The invention relates to combs and more particularly to a comb to be employed by barbers and others in connection with cutting the hair of persons.

15 In cutting hair it is desirable to cut the hair short near the neck of the person and gradually leave the hair longer as the crown of the head is approached. The ordinary comb is usually provided with a square or 20 round edge opposite the teeth, which does not admit of the smooth rolling motion that is necessary to adjust the comb from a position that will produce a short length of hair near the neck and a gradually longer length 25 as the crown of the head is approached. It is understood that the hair is cut with scissors or clippers close to the side of the comb opposite the head from which the hair is cut.

30 As the barber starts to cut the hair near the neck and cuts upward, the square corner or round edge of the ordinary comb is first on the person's neck and then on the mat of uncut hair. The comb does not feel pleasant 35 to the person whose hair is being cut, and the uncut hair does not form a smooth bearing for a square or small round corner.

The present invention has provided an improved comb with the back edge opposite 40 the teeth beveled and forming an arc whose chord lies in an acute angle to the axis of the teeth, presenting a wide smooth rolling surface to the neck and to the hair over which the comb is passed in a rolling motion 45 in the operation of cutting a person's hair.

By presenting a broad curved surface to the person's neck and hair the comb is not unpleasant to the neck and the hair forms a bearing surface over which the comb may 50 be easily moved in a rolling motion, whereas a sharp corner or a round edge does not present sufficient surface to slide evenly over the hair.

With these and other objects in view, the invention consists in the features of construction, form, and combinations of forms here-

inafter set forth, the accompanying drawings illustrating a comb in which the improved features are embodied.

In the drawings:—

Figure 1 is a side view of a comb in which the improved features are embodied.

Fig. 2 is a view of the opposite side of the comb from that shown in Fig. 1.

Fig. 3 is an enlarged sectional view taken 65 on line 3—3 of Fig. 1 and line 3—3 of Fig. 2.

Fig. 4 is an enlarged sectional view taken on line 4—4 of Fig. 1 and line 4—4 of Fig. 2.

The comb 5 is of ordinary form and construction with the usual coarse teeth 6 and 70 fine teeth 7, excepting that the side 8 from the end 9 to the intersection of the coarse and fine teeth at 10 is beveled to form the curve 11 preferably irregular from 12 to 13, while the side 14 from the end 15 to the intersection 10 of the coarse and fine teeth is 75 beveled to form the curve 16 preferably irregular from 17 to 18.

When the coarse teeth 6 of the comb are employed the teeth are started upward into 80 the hair from the neck of the person with the side 8 resting on the neck, and the comb is gradually rolled with the teeth side outward from the hair until the curved portion 11 rests first upon the neck and then on the 85 hair as the comb advances upward through the hair, and no matter to what angle the comb is inclined from the hair the curved portion 11 forms a smooth steady resting surface for the comb. The opposite end of 90 the comb is employed in the same manner with reference to the form thereof.

The improved comb is very advantageous in connection with cutting the hair of persons, as the hair can be cut more evenly 95 and in very much less time, so that the comb improves the quality of the work and saves considerable time, enabling the barber to cut a person's hair in one third the time required when the ordinary comb is employed.

As a further advantage of the particular form of the comb, when the teeth 6 are employed the portion of the comb containing the teeth 7 is grasped in the hand, and passing the teeth 6 upward through the hair has a tendency to bend the end 9 of the comb downward. The curve 11 decreases the quantity of material that would otherwise form the side 8 of the comb and this side is in compression during the foregoing operation, while the curve increases the quantity of 105 110

material that would otherwise form the side 14 of the bar shaped back of the comb and this side is in tension, so that with a given quantity of material the comb is tougher and possesses greater stiffness than a comb with a square or round back edge. The same conditions are true with reference to the opposite end of the comb when the teeth 7 are employed. So that with a given quantity of material the comb is stiffer and stronger against bending stress by reason of the curves 11 and 16.

What is claimed as new, and desired to secure by Letters Patent, is:—

- 15 1. A comb with the back edge thereof

beveled transversely in opposite directions from near the center of the length of the comb longitudinally to each end of the comb, each of the bevels forming an arc whose chord lies in an acute angle to the axis of the 20 teeth.

2. A comb comprising an approximately straight flat bar-shaped back with conventional teeth projecting from one edge of the back, each longitudinal half of the length 25 of the opposite edge of the back of the comb beveled to an arc whose chord lies in an acute angle to the axis of the teeth.

JOSEPH A. CYPERT.
